UNITED STATES PATENT OFFICE

WILHELM FUCHS, OF BUDAPEST, HUNGARY

TIPPING COIN PLATE

Application filed July 7, 1930, Serial No. 466,270, and in Hungary February 27, 1930.

The present invention relates to a tipping coin plate which can be tipped about two supports or pivots in two directions and which is characterized by simplicity of design, ease and reliability of operation, and cheapness of manufacture.

The drawings show a constructional form by way of example of the subject of the invention, namely:

10 Figure 1 is a side elevation and part section through the line 1—1 of Fig. 2, Fig. 2, is a plan view and Fig. 3, a front elevation of the coin plate; Fig. 4, is a side elevation of the tipping tongue or a channel-shaped guide; 15 Fig. 5, is a plan view of the tipping tongue or the guide; Fig. 6, is a side elevation and a plan view of the underlying plate which serves as a bearing (support) during the tipping of the plate and; Fig. 7, a plan view of 20 the plate; Fig. 8, a front elevation of the plate, and finally Fig. 9, a perspective view of the coin plate.

In the constructional form illustrated, to the bottom of the plate *a* there is fixed a 25 metal band *j* bent to U-shape in the middle and designed at both ends as a tipping tongue *g*. From the connecting (coupling) members *j*₁ between the tipping tongues and the U-shaped part, a tongue *k* projects downwards on both sides, which tongues can be 30 accommodated in the grooves *m* of the supporting plate *l* fixed to the base. From both ends of this supporting plate prolongations *n* extend which surround (embrace) the coupling member *j*₁ like a fork, and these are 35 provided with the grooves *m* which serve to receive the tongues *k*. On pressing down the tipping tongue *g* the tongues *k* turn in the grooves *m* in the same manner as if they

40 were mounted in bearings, owing to which the tipping is made reliable and easy. During the tipping movement the curved part of the band *j* moves along the edge *n*₁ of the supporting plate *l*, then the edge *j*₂ of the 45 band strikes against the edge *n*₁ of the sup-

porting plate, which prevents the plate from tipping further than is necessary, which is not the case with the plates, hitherto known.

At both ends of the plate *a* the tipping tongues *g* abut against the plate in such a 50 manner that between the tongue and the bottom face of the plate there is in each case interposed a vertical downward prolongation *h*. At the two ends of the plate where the coin slides off it, a rib *i* directed upwards is 55 in each case pressed in the surface of the plate centrally to the outlet opening.

The prolongation *h* formed between the tipping tongue *g* and the plate prevents the hand which is laid on the tipping tongue 60 from approaching the lower part of the end of the plate because, owing to the prolongation *h* between the plate end and the hand surface, a space or distance is formed which remains even during the tipping movement, 65 which renders possible the unhindered sliding down of the coin into the hand surface, while if this prolongation *h* were omitted, the coin collecting on the hand surface lying in front of the plate would prevent the sliding 70 down of further coins from the plate. The ribs *i* also prevent congestion of the coins because the inner edge of the coin sliding on this rib is lifted off slightly from the plate so that jamming (seizing) in the outlet 75 opening can be prevented in this way, consequently the coin slides more easily away from the plate.

The plate itself is suitably provided with 80 advertisements which, during the fitting of the plate act as a very effective moveable advertisement.

I claim:

1. A tippable coin plate wherein a V shaped metallic band for guiding said plate during tipping is provided, in combination, 85 tongues carried by the extremities of said band for tipping said plate, trunnions for said plate, said trunnions being formed by 90 tongues formed out of the horizontal parts of

the legs of said metal band and protruding downwards, a base plate, fork-like projections protruding from said base plate said projections gripping said guide band on two sides and grooves in said projections for accommodating said trunnions.

5. A tippable coin plate as claimed in claim 1 characterized in that the trough of the tipping tongue reaches behind the plane 10 of the leg member protruding vertically downward at both extremities of the plate so that when the finger is laid into this trough it cannot slide upward by reason of the vertical leg member.
